PAGE 3

FIG. 3

FIG. 4

FIG. 5

FIGURE 1 is an elevational view of the external side of a combined brake drum and wheel showing my new design;

FIGURE 2 is an elevational view of the internal side;

FIGURE 3 is a vertical cross sectional view taken on line 3—3 of FIGURE 1;

FIGURE 4 is a front perspective view; and

FIGURE 5 is a rear perspective view.

I claim:

The ornamental design for a combined brake drum and wheel, substantially as shown.
